UNITED STATES PATENT OFFICE

LEWIS H. McCARRON, OF SIERRA MADRE, CALIFORNIA, ASSIGNOR TO ELECTRIC SIGN
FLASHER CORPORATION, OF LOS ANGELES, CALIFORNIA

FLASH-SIGNALING DEVICE

Application filed June 10, 1929. Serial No. 369,662.

In signals it is of very great importance that the same shall be instantly seen, in order that the command thereof be obeyed. If the signal is continuous, it is not as apt to be observed as if it is intermittent. It is therefore of the essence of my invention to provide an intermittent signaling device which when set will be intermittent and automatic in operation until released.

10 In the description of my signaling device, I shall show it and describe it as applied to an automobile, but do not limit myself to its use on an automobile as it has various other uses.

15 The drawing forming a part of this application is a diagrammatic illustration of my invention applied to an automobile, a portion of which is shown diagrammatically.

Referring to the drawings, 1 is a fragment 20 of the chassis of an automobile, and 2 is a portion of the foot brake lever. Mounted in the chassis is a source of electricity shown as a battery, 3. The chassis 1 has secured thereto a base plate 4, on which is pivotally mounted by pin 5 a contact lever 6 on the lower end of which is contact 7 that is insulated therefrom by insulating washers 8. Adjacent to lever 6 and pivotally mounted on plate 4 by pin 5 is a second contact lever 9, on the lower 25 end of which is contact 10 that is insulated therefrom by insulating washers 11. Secured to lever 6 between pivot 5 and contact 7 is a thermo-expansive wire 12, which is insulated from lever 6. The outer end of wire 12 is secured to a stud 13 mounted on plate 4, and is insulated from said stud. A magnet coil 14 is mounted on plate 4 and has one side thereof connected to wire 12 at stud 13 by wire 15. The other side of coil 14 is connected to contact 10 by wire 16. A branch wire 17 connects wire 16 to signal 18. One side of battery 3 is connected by wire 19 with the inner end of wire 12. The other side of battery 3 is connected by wire 20 to contact 7. The other 35 side of signal 18 is connected to wire 19 by wire 19. An operating lever 21 is pivotally mounted on plate 4 adjacent to the upper end of lever 9, and is adapted when the upper end thereof is moved to the left to rock lever 9 and thereby cause contacts 7 and 10 to engage. Lever 9 is so located that its upper end forms an armature for coil 14. A rod 22 is connected to lever 21 and passes through a guide lug 23 mounted on plate 4. A safety spring 24 connects rod 22 with lever 2. A 55 spring 25 coiled around rod 22 between lug 23 and lever 21 normally holds lever 21 from engaging contact lever 9. A spring 26 secured to lever 9 and to plate 4 normally holds lever 9 from carrying contact 10 into engagement with contact 7. A spring 27 secured to the upper end of contact lever 6 and to plate 4 keeps wire 12 taut when it expands, as hereafter stated. A stop 28 holds lever 21 from moving too far to the left.

In the operation of my device, when the brake lever is moved to apply the brakes, lever 21 moves contact lever 9 to cause contacts 7 and 10 to engage, thereby causing current to flow through the coil and through 70 thermo-expansive wire 12 and its connections, and also through stop signal 18. Wire 12 soon becomes heated and expands, thereby permitting spring 27 to rock lever 6 to carry contact 7 to the right. At the same time 75 magnet 14 causes its armature to also move contact 10 to the right thereby maintaining engagement between contacts 7 and 10, a longer time than if the magnet were omitted. The further expansion of 12 permits spring 80 27 to cause the separation of contacts 7 and 10, thus stopping the flow of current through coil 14 and signal 18. Wire 12 quickly cools and contracts and draws lever 6 to again cause contacts 7 and 10 to engage. It will be observed that after magnet 14 is energized, it exerts a pull upon its armature 9 and as wire 12 becomes heated and begins to expand, the pull upon armature 9 keeps contacts 7 and 85 10 in engagement until the expansion of wire 12 permits spring 27 to pull lever 6 to cause the separation of contacts 7 and 10 thereby breaking the current through magnet 12 which then releases the pull of its armature 9 and contacts 7 and 10 separate with a snap 90 thereby avoiding objectionable arcing.

Thereafter, the operations are repeated as long as the brake lever is applied. When pressure is removed from the brake lever, the parts resume normalcy. Other means than a 100

brake lever can be used to move lever 21 to cause lever 9 to carry contact 10 into engagement with contact 7. When the flash signal 18 is used in other structures, lever 21 and parts thereafter mentioned would be omitted and suitable means would be provided for causing the engagement of contacts 7 and 10 and a stop would be provided for the upper end of lever 9.

5 10 Having thus described my invention I claim:

15 A flash signal device comprising a source of electricity; a magnet coil operated thereby; a flash signal connected in shunt to the coil circuit; a switch in said coil circuit; springs connected to said switch members adapted to cause the separation of said members; and a thermo-expansive wire forming a 20 part of the magnet coil circuit and when cool adapted to keep the switch members of the coil circuit in engagement, and when heated to permit said switch members to be disengaged by the springs connected thereto.

25 In witness that I claim the foregoing I have hereunto subscribed my name this 4th day of June, 1929.

LEWIS H. McCARRON.
